UNITED STATES PATENT OFFICE.

CHARLES H. DRIVER, OF RACINE, WISCONSIN, ASSIGNOR TO C. H. DRIVER & KERR CO.,
OF RACINE, WISCONSIN.

SANDPAPER BELTING.

1,126,423.

Specification of Letters Patent. Patented Jan. 26, 1915.

Application filed February 4, 1914. Serial No. 816,651.

To all whom it may concern:

Be it known that I, CHARLES H. DRIVER, a citizen of the United States, residing at Racine, in the county of Racine and State 5 of Wisconsin, have invented a new and useful Sandpaper Belting, of which the following is a specification.

The present invention aims to provide, as an article of manufacture, a strip of abrasive material which may be dispensed to 10 customers in the form of a roll or otherwise, the construction being such that, by merely tearing off a strip from the roll, a section is formed, the ends of which are beveled, so 15 that when these ends are overlapped and secured together, a belt will be formed, which belt at its joint, will be of approximately the same thickness as the original thickness of the material.

20 A further object of the invention is to provide a process whereby a strip of abrasive material may be adapted for use in the formation of a sand belt so called.

It is within the scope of the invention to 25 improve generally, the construction of sand belts, and to improve processes whereby a strip of material is adapted for use in the formation of a sand belt.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawing:—Figures 40 1, 2 and 3 are longitudinal sectional views illustrating various steps in the manufacture of a sheet of abrasive material for use in a sand belt; Fig. 4 is a perspective showing a strip of material disposed in roll form; 45 Fig. 5 is a perspective showing a detached strip having its ends united to form a belt; Fig. 6 is a fragmental longitudinal section illustrating in detail, the appearance of the ends of the strip at the point of joining; 50 Fig. 7 is a longitudinal sectional view showing a modified form of the invention.

In the accompanying drawing, the numeral 1 indicates generally a strip of sand

paper. In this connection, the word "sand" is to be construed as meaning any abradant 55 and the word "paper" is to be construed as meaning any flexible substance to which an abradant may be attached.

The sheet of sandpaper comprises a flexible body 2 carrying an abrasive indicated 60 at 3. The sheet or strip may be of any desired length and originally appears as shown in Fig. 1 of the drawing. In the abrasive face of the strip there is formed a recess 4 defining a bevel 5 in the body 2 and defining 65 bevels 6 and 7 in the abradant 3, the article then appearing as shown in Fig. 2.

In the under face of the strip and more specifically in the body 2 there is formed a recess 8. This recess 8 overlaps the recess 4 70 longitudinally of the strip.

By the operation above described, a bevel 9 will be formed in the under face of the body portion 2 of the strip, the article now appearing as shown in Fig. 3. It is to be 75 observed that by the process as thus far carried out, the strip is thinnest at 10, at a point adjacent the bevel 7. The concavities above referred to extend entirely across the strip of material and are formed 80 at intervals. Ordinarily, the strip, having been cut away upon its opposed faces at spaced intervals, as shown in Fig. 3, is formed into a roll 11, as depicted in Fig. 4. The article is now in condition for sale. 85

The user, having before him the roll 11, unwraps therefrom a portion of the roll, and tears off a section at the point 10. Since this point 10 is adjacent one edge of 90 the abradant 3, which edge may be taken to be represented by the bevel 7, it may be observed that the abradant at this point serves to stiffen the strip and facilitates the tearing off of the section. After a section has been detached from the roll 11, the ends of 95 the section are brought together to form a belt as shown at 12 in Fig. 5, the bevel 9 being overlapped upon the bevel 5 as shown in Fig. 6, the beveled faces 5 and 9 being cemented together or otherwise secured to 100 form the joint 14 in the belt 12. By the operation above described the belt is of approximately the same thickness at the joint as elsewhere. Further, owing to the formation of the bevels 6 and 7 in the abradant 105 there is no abrupt joint where the ends of

the section are brought together to complete the configuration of the belt as shown in Fig. 5.

The importance of the present invention will be readily understood when it is noted that the purchaser desiring a sand belt merely unwraps a section from the roll, tears off the section, and unites the beveled ends, it being unnecessary to scarf, pare or otherwise operate mechanically upon the ends of the section, in order to obtain a satisfactory joint. Although the concavities 4 and 5 are shown as of straight line configuration, longitudinally of the belt, it will be understood readily that the concavities may be varied in outline, Figs. 2 and 3 being largely diagrammatic in nature.

In Fig. 7, a modified form of the invention is depicted. The strip is indicated at 20 and comprises a flexible body 21 and an abrasive 22 thereon. In the abrasive face of the strip there is shown a recess 23, defining a bevel 24 in the body 21 and defining bevels 25 and 26 in the abrasive 22. In the under face of the strip there is formed a recess 27 defining a bevel 28. The thinnest points in the strip are indicated at 29. It is at these points 29 that the strip is severed. In the

form of invention under discussion, a comparatively short piece of waste material indicated at 30 results.

Having thus described the invention, what is claimed is:—

1. As an article of manufacture for use in the formation of belts, a strip of abrasive material having spaced pairs of concavities extended thereacross at intervals, the concavities of the respective pairs being formed in opposed faces of the strip.

2. As an article of manufacture for use in the formation of belts, a strip of abrasive material having concavities extended entirely thereacross, at intervals, the concavities being spaced from each other to define belt lengths and certain of the concavities lying between the ends of the strip to facilitate the separation of a belt length from the strip.

In testimony that I claim the foregoing as my own, I have hereto affixed my signature in the presence of two witnesses.

CHARLES H. DRIVER.
